(57) **CLAIM**

We claim, the ornamental design for a luminaire, as shown and described.

DESCRIPTION

FIG. 1 is a first perspective view of an exemplary embodiment of the invention;

FIG. 2 is a second perspective view of the exemplary embodiment of FIG. 1;

FIG. 3 is a side plan view of the exemplary embodiment of FIG. 1, the luminaire being symmetric about a center axis;

FIG. 4 is a top plan view of the exemplary embodiment of FIG. 1; and,

FIG. 5 is a bottom plan view of the exemplary embodiment of FIG. 1.

The phantom lines shown in FIG. 1-FIG. 5 are environmental and not part of the claimed design.

The color of the luminaire forms no part of the claimed design, a luminaire according to the claimed design may be of any color or combination of colors.

The dot-dash-dot lines shown in FIGS. 1-5 indicate that the degree of transparency and/or opaqueness of the globe of the luminaire forms no part of the claimed design. The globe of the claimed design may including faceting.

The surface treatment of the luminaire forms no part of the claimed design, a luminaire according to the claimed design may have any surface treatment.

References to "side", "top", and "bottom" in the figure descriptions are not meant to require certain in-use orientation, a luminaire according to the claimed design may be used in any orientation.

1 Claim, 5 Drawing Sheets
